UNITED STATES PATENT OFFICE.

GEORGE W. MANNING, OF CHICAGO, ILLINOIS.

BROOM.

1,409,560.

Specification of Letters Patent. Patented Mar. 14, 1922.

Application filed March 21, 1918. Serial No. 223,812.

To all whom it may concern:

Be it known that I, GEORGE W. MANNING, a citizen of the United States, residing at Chicago, in the county of Cook and State 5 of Illinois, have invented certain new and useful Improvements in Brooms, of which the following is a specification.

My invention relates to brooms and has for its primary object the provision of improved means whereby a body of bristles and a handle for welding the same may be held together. Other objects are the provision of handle holding devices of great strength and whereby wear in the handle may be 10 taken up to prevent looseness of the handle; the provision of clamping plates having improved strengthening and bristle gripping elements whereby a body of bristles may be bound into a firm mass; and the provision 15 of a spring for preventing loosening of a rotatable handle holding member.

Other objects and advantages of my invention will appear from the following description taken in conjunction with the accompanying drawings which form a part of this specification and illustrate the preferred embodiment of the invention.

In the drawings:

Fig. 1 is a front elevation of a broom embodying my improvements, the upper part of the handle being broken away.

Fig. 2 is a section taken on line 2—2 of Fig. 3.

Fig. 3 is a section taken on line 3—3 of Fig. 2.

Fig. 4 is a section taken on line 4—4 of Fig. 3.

Fig. 5 is a fragmentary side elevation of the broom shown in the preceding figures, 40 this view being taken from the right hand side of Fig. 1.

A body 10 of upstanding bristles of broom corn or other suitable material is bound together into a firm mass at its upper end 11 by companion front and rear clamping plates numbered 12 and 13 respectively. A pair of opposed, semi-cylindrical handle holding shanks 14 and 15 rise respectively from the front and rear plates and define a socket for 45 the handle 16, the latter being shouldered at 17 to fit flush with the shanks. The shanks are elongated vertically in order that they may grasp the handle at upper and lower

points considerably spaced from each other. Each shank is integral with its clamping plate and both are preferably formed of a sheet metal stamping. Each shank is formed with a longitudinal stiffening corrugation 18 and with transverse stiffening upper and lower corrugations 19 and 20 respectively 55 which intersect the upper and lower extremities of the corrugation 18. These transverse corrugations preferably extend from one longitudinal edge to the other in each shank but are spaced from the extremities 60 of the shank. Oppositely registering apertures are punched in the corrugations 18, and the forward shank is countersunk about this aperture to receive smoothly the screw head of a threaded bolt 21 which passes 70 through the handle 16, while the rear shank has a squared depression formed about it in the metal to receive and prevent rotation of a nut 22 threaded on the bolt. The bolt head and nut are positioned approximately 75 at the longitudinal and transverse centers of the respective shanks, and the latter are cambered on horizontal axes at these centers; that is, they are given a slight curve from top to bottom to cause their upper and 80 lower extremities to exert greater pressure against the handle than their central portions. By means of this construction the handle is prevented from pivoting in the shanks about a horizontal axis passing 85 through the bolt at right angles to it, as would be the case were the centers of the shanks drawn tightly against the wood of the handle. When the handle becomes worn where the extremities of the shanks bear on 90 it, this wear can be taken up by rotating screw bolt 21 in nut 22 to close the slight space shown in Fig. 2 between the socketed cylindrical portion 23 of the handle and the central portions of the shanks. The corrugations 18 carry the tension of the bolt upwardly and downwardly along the shanks, and the transverse corrugations 19 and 20 carry this pressure around the handle, thereby preventing the edges of the shanks from 95 100 curling away from the handle.

The clamping plates are held against the body of bristles by a central clinch pin 24, intermediate pins 25, and end pins 26. The central pin is formed of spring metal and 105 has its tip 27 bent back through plate 13 to

a position above and spaced from its body portion, this tip, before insertion of the handle, occupying the position shown by the up-tilted dotted lines in Fig. 2. The 5 stampings comprising the plates and shanks are so formed that the lower extremities of the shanks approach each other to form a downwardly tapering socket, the diameter of this socket, just above tip 27, being slightly 10 less than the diameter of the lower end of the handle. In setting the handle, as it is wedged into the shanks, it strikes the up-tilted tip 27 and forces this down into the full line position of Fig. 2; bolt 21 is now 15 driven through the shanks and handle and threaded into nut 22, drawing the upper ends of the shanks tightly against the handle just below shoulder 17. Should the handle wear loose in the shanks before 20 bolt 21 is screwed up to tighten their hold, the bolt can never turn out of the nut because of the constant upward pressure of tip 27 communicated through the handle to the bolt and through the bolt to the upper 25 edges of the shank apertures.

As best seen in Figs. 1 and 4, the clamping plates 12 and 13 have their upper and lower longitudinal edges inbent to form strengthening and bristle gripping edge members 28 30 and 29. Between these longitudinal edges, and substantially paralleling them, are medial strengthening and bristle gripping members comprising in each plate an in-turned corrugation 30. These corrugations 35 30 are discontinuous to permit the formation between their spaced ends of centrally apertured circular corrugations 31 against which the heads 32 of the clinch pins bear. These circular corrugations are formed only in the 40 front clamping plate 12, and they serve to strengthen the plate by distributing the pressure of the heads 32 toward the edges of the plate.

Viewing Fig. 2, it will be seen that elongated corrugations 33, pierced at each end, 45 are formed in the rear plate 13 to receive the bends of the clinch pins and distribute the pressure of those pins through the plate.

At its extremities each plate is provided 50 with an end ear 34. The ends of the bristles extend slightly above the upper edge flanges 28 and protected by a cover 35 which is of an inverted U-shape in cross section. Each cover has its inner end 36 wedged between 55 the lower end of the handle and the side of a recess 37 formed in the firm mass 11 for reception of the handle; while the outer end of each cover is positioned between the overlapped ears 34 of the front and rear clamping 60 plates. By means of a horizontal corrugation 38 formed in both ears and in the outer end of each cover, the covers are secured between the ears. These corrugations 38 are inturned and positioned above the end 65 clinch pins 26 so that those bristles lying

between the end pins will be forced against the outer side of the pin at each side of the broom and bent over the pin, being thereby held securely against loosening.

In the manufacture of the lighter grades 70 of brooms the fineness of the bristles used causes too great flexibility in the brushing action of the finished article. To provide the requisite stiffness, I insert thick, stiff bristles 39 in the firm mass 11 and extend 75 them downwardly below the clamping plates to substantially the location of the customary stitching 40 shown in Fig. 1.

By inserting a screw-driver in the head 80 of bolt 21 the handle may be removed by withdrawal of the bolt and used in a new broom.

I claim:

1. In a broom, the combination with a body of bristles, of companion clamping 85 plates therefor, a pair of opposed shanks formed one on each plate and defining a handle socket, said shanks tapering toward each other at their junctions with the respective plates, a yieldable pin extending 90 through the plates and said body below said socket and having a yieldable portion disposed within the socket, and a handle wedged into the tapered portion of the socket and bearing on the yieldable portion 95 of said pin.

2. In a broom, the combination with a body of bristles, of companion clamping plates therefor, a pair of opposed shanks formed one on each plate and defining a 100 handle socket, a pin of spring metal binding the plates against said body and having its tip bent back above and spaced from its body portion so that said tip extends into the bottom of the socket, a handle in the socket 105 and bearing on said tip, and a bolt passing through the handle and shanks and holding the shanks against the handle; said tip being compressed, whereby it exerts pressure 110 through the handle and against the bolt to prevent rotation of the bolt.

3. In a broom, the combination with a body of bristles, of a clamp therefor, a handle socket carried by the clamp, a handle in the socket, a bolt passing through the handle 115 and socket, and a pin of spring metal mounted in the clamp and exerting pressure through the handle against the bolt to prevent rotation of the bolt.

4. In a broom, the combination with 120 companion bristle clamping plates, of a body of bristles bound therein, a pin traversing said body and the plates near corresponding ends of the plates, overlapped end ears fixed one on each plate and binding a portion of said 125 bristles against the outer side of the pin, and interfitting strengthening corrugations formed one in each ear above the pin and in-turned to bind said portion of the bristles over the pin. 130

5. In a broom, the combination with a handle, a body of bristles, and clamping elements binding the bristles into a firm mass, there being a handle receiving recess formed centrally in the top of said mass; of overlapped end ears formed on said elements, covers for the top of the bristles each having its inner end inserted between the handle and the side of said recess and its outer end positioned between said ears, and interfitting strengthening and locking corrugations formed in said ears and the outer ends of the covers. 10

GEORGE W. MANNING.
